DESIGN FOR A DRESS ENSEMBLE OR SIMILAR ARTICLE

Abraham H. Morris, New York, N. Y.

Application November 18, 1937, Serial No. 73,000

Term of patent 3½ years

To all whom it may concern:

Be it known that Abraham H. Morris, a citizen of United States and resident of New York city, in the county of New York, State of New York, has invented a new, original, and ornamental Design for a Dress Ensemble or Similar Article, of which the following is a specification, reference being had to the accompanying drawing, forming part thereof, and in which,

Fig. 1 is a front view of a dress ensemble showing my design,

Fig. 2 is a front view of the dress unit of the ensemble shown in Fig. 1,

Fig. 3 is a rear view of Fig. 2, and

Fig. 4 is a rear view of the jacket unit of the ensemble shown in Fig. 1.

I claim:—

The ornamental design for a dress ensemble or similar article substantially as shown.

ABRAHAM H. MORRIS.
